UNITED STATES PATENT OFFICE.

HOMER P. BARLOW, OF WATERTOWN, CONNECTICUT.

DESIGN FOR A BABY-CARRIAGE ROBE.

SPECIFICATION forming part of Design No. 25,134, dated February 4, 1896.

Application filed November 25, 1895. Serial No. 570,115. Term of patent 7 years.

To all whom it may concern:

Be it known that I, HOMER P. BARLOW, a citizen of the United States, residing at Watertown, in the county of Litchfield and State of Connecticut, have invented and produced a new and original Design for a Baby-Carriage Robe; and I do hereby declare the following to be a full, clear, and exact description of the invention, such as will enable others skilled in the art to which it appertains to make and use the same.

Referring to the accompanying drawings, Figure 1 is a plan view of my new design, and Fig. 2 a sectional elevation taken on the line $x x$ of Fig. 1.

The leading features of my new and original design for baby-carriage robes are a robe which, when spread out, has the general shape of the skin of a four-legged animal and is bounded along the sides by generally concavo-convex lines, while at the top of the robe the corners diverge and extend to present the appearance of a skin which has been removed from the hind legs of an animal, a false tail attached and projecting from the robe at a point midway between said corners, the border and lining of the robe being of one piece of felt or other suitable material, and the semi-circular slit in the body of the robe.

In the accompanying drawings, 1 is the body 30 of the robe, of the general shape of the skin of a four-legged animal and bounded along the sides by concavo-convex lines; 1^a, the corners, which diverge and extend from the top of the robe to present the appearance of the skin 35 removed from the hind legs of an animal; 2, the false tail, which projects from the robe midway between said corners; 3, the border and lining, and 4 the semicircular slit in the body of the robe. 40

When in use, the robe is placed in such manner in the carriage as to have the child's head and arms protrude through the slit 4, and in this position the flap, which is made by slitting the robe as above described, acts 45 as a chest-protector for the child.

I claim—

The design for carriage-robés, substantially as shown in the accompanying drawings.

In testimony whereof I affix my signature 50 in presence of two witnesses.

HOMER P. BARLOW.
